US0D1105043S

(12) **United States Design Patent** (10) **Patent No.:** **US D1,105,043 S**
(45) **Date of Patent:** **** Dec. 9, 2025**

(54) **NETWORK GATEWAY**

(71) Applicant: **Siemens Aktiengesellschaft**, Munich (DE)

(72) Inventors: **Hui Zou**, Chengdu (CN); **Chang Sen Chen**, Chengdu (CN); **Zhan Bo Ren**, Chengdu (CN)

(73) Assignee: **Siemens Aktiengesellschaft**, Munich (DE)

(**) Term: **15 Years**

(21) Appl. No.: **29/855,883**

(22) Filed: **Oct. 7, 2022**

(30) **Foreign Application Priority Data**

Apr. 8, 2022 (CN) 202230195245.X

(51) **LOC (15) Cl.** **14-03**

(52) **U.S. Cl.**

USPC **D14/240**; D14/242

(57) **CLAIM**

The ornamental design for network gateway, as shown and described.

DESCRIPTION

FIG. 1 is a front elevation view of a network gateway, showing our new design;

FIG. 2 is a rear elevation view thereof;

FIG. 3 is a top plan view thereof;

FIG. 4 is a bottom plan view thereof;

FIG. 5 is a right elevation view thereof;

FIG. 6 is a left side view thereof;

FIG. 7 is a top, front and left side perspective view thereof; and,

FIG. 8 is a bottom, rear and right side perspective view thereof.
